Evan R. Witt(57) **CLAIM**

The ornamental design for an electrical bus bar assembly as shown and described.

DESCRIPTION

FIG. 1 is a perspective view of an electrical bus bar assembly showing our new design;

FIG. 2 is another perspective view thereof;

FIG. 3 is a further perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines in the figures are for the purpose of illustrating portions of the electrical bus bar assembly and form no part of the claimed design.
